[57] CLAIM

The ornamental design for a telephone kiosk, as shown and described.

DESCRIPTION

FIG. 1 is a front perspective view of a telephone kiosk showing my new design;
FIG. 2 is a front elevational view thereof;
FIG. 3 is a rear elevational view thereof;
FIG. 4 is a side elevational view thereof, the view of the other side being a mirror image of this view;
FIG. 5 is a top plan view thereof;
FIG. 6 is a perspective view of a second embodiment of that shown in FIG. 1;
FIG. 7 is a front elevational view thereof;
FIG. 8 is a rear elevational view thereof;
FIG. 9 is a side elevational view thereof, the view of the other side being a mirror image of this view;
FIG. 10 is a top plan view thereof;
FIG. 11 is a perspective view of a third embodiment of that shown in FIG. 1;
FIG. 12 is a front elevational view thereof;
FIG. 13 is a rear elevational view thereof;
FIG. 14 is a top plan view thereof;
FIG. 15 is a right side elevational view thereof;
FIG. 16 is a left side elevational view thereof;
FIG. 17 is a perspective view of a fourth embodiment of that shown in FIG. 1;
FIG. 18 is a front elevational view thereof;
FIG. 19 is a rear elevational view thereof;
FIG. 20 is a top plan view thereof;
FIG. 21 is a right side elevational view thereof; and,
FIG. 22 is a left side elevational view thereof.
